ROTARY BUFFING TOOL

Elisha W. Hall, Scituate, and Albin S. Rock, Rockland, Mass., assignors to F. L. & J. C. Codman Company, Rockland, Mass., a corporation of Massachusetts

Application February 1, 1941, Serial No. 377,962

13 Claims. (Cl. 51—193)

This invention relates to rotary abrading tools of the class employing a ring of abrading material about and secured to a hub, and to be associated with other like assemblies coaxially disposed on and about an arbor and secured to the latter by clamping plates and a clamping nut threaded onto the arbor. The invention aims to overcome some of the disadvantages of prior tools of this class, and among its aims are (1) to simplify the construction by the elimination of certain parts heretofore employed, (2) to reduce the cost of manufacture, (3) to reduce the cost of replacing the abrading element from time to time, (4) to secure the abrading element to the hub without the use of parts other than a simple, one-piece hub, (5) to render the application of the abrading element to and its removal from the hub rapid and convenient, and (6) to increase the durability of the abrading element. Other aims and advantages will appear during the course of the following description or will be obvious to those skilled in the art.

The invention will best be understood by reference to the following description when taken in connection with the accompanying drawings of one specific embodiment thereof, while its scope will be pointed out more particularly in the appended claims.

In the drawings:

Fig. 1 is an elevation of an assembly of a hub and a circumferential abrading element to be associated with other like assemblies on an arbor;

Fig. 2 is an elevation of the assembly as viewed from the right-hand side of Fig. 1;

Fig. 3 is a sectional view on line 3—3 of Fig. 2;

Fig. 4 is a plan of the assembly with the fold of the abrading element opened to display the means of attachment of the abrading element to the hub;

Fig. 5 is an elevation illustrating the mode of spirally winding a bias-cut strip of cloth to start the making of the abrading element;

Fig. 6 is an elevation viewed from the right-hand side of Fig. 5;

Fig. 7 is a plan on an enlarged scale of a portion of the spirally-wound, bias-cut strip showing, not only obliquely disposed stitching connecting two pieces, end to end, but also two rows of stitching attaching the plies of the spirally-wound strip together;

Fig. 8 is a plan illustrating the next step of providing the laminated ring with button holes and with openings to reduce the bulk of the central portion of the strip;

Fig. 9 is an elevation illustrating the folding of the ring; and

Fig. 10 is a plan illustrating the step of attaching the ring to the hub.

Referring to the drawings and to the embodiment of the invention illustrated therein by way of example, there is shown in Figs. 5 and 6 a bias-cut strip 12 of cloth being wound spirally on and about a drum 14 to the required thickness, after which the laminated cloth ring is removed axially. To attain sufficient thickness, it will be desirable to make the strip of a number of bias-cut pieces joined end to end by diagonal stitching 16 shown in Fig. 7. After winding, the convolutions 15 are suitable secured together as by two rows of stitching 18 extending through the several thicknesses and disposed lengthwise of the strip.

The strip is now in the form of a cylindrical, laminated ring 20 which is to be disposed circumferentially about and secured to a simple, one-piece hub which is in the nature of a plate 22 (see Fig. 1) of appropriate material such as aluminum, provided with a central aperture 24 to receive a usual arbor, not shown, on which several of the assemblies will be mounted coaxially between usual clamping plates and forced axially together by a usual nut, not shown, threaded onto the arbor.

This plate 22 is provided with a circumferential series of generally radial, T-shaped lugs 26, each of which comprises a neck 28 and a circumferentially elongated head 30 having two oppositely extending projections 32. The abrading ring 20 is interlocked with the lugs 26 as by being provided with a series of slots 34 which receive the necks 28 of the T-shaped lugs 26. These slots are sufficiently long to admit of the passage of the heads therethrough when the slots are registered with the heads, by passing first one and then the other of the projections 32 through the slot (see Fig. 10) after which the slot is turned out of registration with the head so as to occupy a position oblique thereto (see Fig. 4). Thus, the ring and the hub are securely interlocked by relative movement of the slots about generally radial axes of the necks. As shown, increased durability of the edges of the slots 34 is attained by "button-hole" stitching 36 about the slots.

The ring 20 is now folded (see Fig. 3), and to avoid undue bulkiness at the fold, the ring is provided with a centrally disposed row of openings 38 (see Figs. 8 and 9). The ring, when thus applied to the hub and folded circumferentially forms radial pleats or folds 40 (see Fig. 1) which overlap adjacent areas, and the ring is now suffi-

ciently compact so that the assembly can be combined with other like assemblies face to face on and about an arbor in the usual fashion. When the ring has become worn sufficiently to require replacement, the ring can be removed quickly and conveniently by a reversal of the foregoing operation, and replaced by another ring.

Having thus described one embodiment of our invention, what we claim and desire, by Letters Patent, to secure is:

1. A rotary abrading tool comprising, in combination, a hub, and an elongated strip of abrading material wound circumferentially to form a ring about said hub, said ring having a series of slots and said hub having a series of parts interlocked with slots and detachable therefrom by relative movement of said slots and said parts about generally radial axes.

2. A rotary abrading tool comprising, in combination, a hub provided with a circumferential series of projections, and a continuous strip circumferentially disposed, and constituting an uninterrupted abrading band about said hub and provided with a series of openings interlocked with said projections.

3. A rotary abrading tool comprising, in combination, a hub having a circumferential series of T-shaped, radial projections each having a neck and a head, and a continuous, unbroken strip circumferentially disposed, and constituting an uninterrupted abrading band having a series of slots about said necks, respectively and disposed obliquely with relation to said heads.

4. A rotary abrading tool comprising, in combination, a hub having a circumferential series of projections, and a continuous strip circumferentially disposed, and constituting an uninterrupted abrading band about said hub and interlocked with said projections, said band being folded circumferentially to provide an uninterrupted annular fold and said projections entering into the fold.

5. A rotary abrading tool comprising, in combination, a hub having a circumferential series of projections, and a continuous strip circumferentially disposed, and constituting an uninterrupted abrading band about said hub and provided with a series of slots interlocked with said projections, said band being folded circumferentially to provide an uninterrupted annular fold and said projections entering into the fold, said band being provided with a series of apertures reducing its bulk along the fold and between said projections.

6. A rotary abrading tool comprising, in combination, a circumferentially folded and radially pleated, bias-cut, continuous strip of cloth constituting an uninterrupted abrading ring provided with a series of openings in its fold, and a hub provided with a series of projections received partly in said openings, and partly in said fold respectively, and securing said ring to said hub.

7. A rotary abrading tool comprising, in combination, a circumferentially folded and radially pleated, bias-cut, continuous strip of cloth constituting an uninterrupted abrading ring provided with a series of openings in its fold, and a hub provided with a series of projections comprising necks received in said openings and heads received within the fold and retaining said ring in place on said hub.

10 8. A rotary abrading tool comprising, in combination, a hub, and a bias-cut strip of cloth wound spirally about and continually receding from the axis of said hub and forming a laminated ring disposed about said hub and having an annular fold adjacent to said hub, said ring having passages extending radially through said laminations and means extending from said hub radially through said passages, and into the interior of said fold to secure said ring to said hub.

15 9. A rotary abrading tool comprising, in combination, a hub, and a continuous strip of abrading material constituting an uninterrupted band wound spirally about and continually receding from the axis of said hub, thus presenting a laminated ring, the laminations being provided with a series of sets of registering openings forming passages radially through said ring, said hub being provided with a series of projections extending radially outward through said passages.

20 30 10. As a new article of manufacture an abrading element for a rotary abrading tool, the same consisting of a strip of cloth wound spirally about and continually receding from a center and forming a laminated ring having slots extending radially through the laminations.

35 11. As a new article of manufacture an abrading element for a rotary abrading tool, the same consisting of a strip of cloth wound spirally about and continually receding from a center and forming a laminated ring having slots extending radially through the laminations, said slots being disposed at an angle to the longitudinal edges of said strip.

40 45 12. As a new article of manufacture an abrading element for a rotary abrading tool, the same consisting of a strip of cloth wound spirally about and continually receding from a center and forming a laminated ring having slots extending radially through the laminations, said slots being obliquely disposed with reference to the longitudinal edges of said strip.

50 55 13. As a new article of manufacture an abrading element for a rotary abrading tool, the same consisting of a strip of cloth wound spirally about and continually receding from a center and forming a laminated ring having slots extending radially through the laminations, said laminations being secured together by at least one row of stitching extending through the several thicknesses and disposed lengthwise of said strip.
